CHRISTMAS TREE STAND

Donald A. Schulz, Wauwatosa, Wis., assignor to S-B
Manufacturing Co., Ltd., Milwaukee, Wis.

Filed Jan. 29, 1973, Ser. No. 327,253

Term of patent 14 years

Int. Cl. D6—99

U.S. Cl. D6—105

FIG. 1 is a top view of a Christmas tree stand showing the design of my invention.

FIG. 2 is a side view of the design of FIG. 1, taken in line with any leg.

FIG. 3 is a cross-sectional view on line 3—3 of the design of FIG. 1 showing the contours of the design.

I claim:

The ornamental design for a Christmas tree stand, as shown.
